UNITED STATES PATENT OFFICE.

LARS W. BODINSON, OF AURORA, ILLINOIS, ASSIGNOR TO THE AMERICAN WELL WORKS,
OF AURORA, ILLINOIS, A CORPORATION OF ILLINOIS.

PUMPING MECHANISM.

1,321,804.

Specification of Letters Patent. Patented Nov. 18, 1919.

Application filed October 14, 1916. Serial No. 125,721.

To all whom it may concern:

Be it known that I, LARS W. BODINSON, a citizen of the United States, and a resident of Aurora, in the county of Kane, State of Illinois, have invented certain new and useful Improvements in Pumping Mechanism, of which the following is a specification, reference being had to the accompanying drawings.

10 My invention relates to pumping mechanism and particularly to a new and improved arrangement of driving means for connecting a horizontal engine to the vertically extending shaft of a deep well centrifugal or turbine pump. It is one of the objects of my invention to provide new and improved means for oiling the working parts of such a connecting means. It is another object of my invention to provide new 15 and improved means for cooling the gearing and bearings of the pump head. It is another object of my invention to improve mechanisms of this type in sundry details hereinafter pointed out. The preferred 20 means by which I have accomplished my several objects are illustrated in the drawings and are hereinafter specifically described. That which I believe to be new 25 and desire to cover by this application is set forth in the claims.

In the drawings:—

Figure 1 is a central vertical section through a pump head embodying the preferred form of my improvements.

Fig. 2 is an enlarged detail, partly in section, illustrating a split collar construction forming a part of the connecting means between the pump shaft and the lowermost thrust bearing for supporting the vertical 40 gear;

Fig. 3 is a top view of one end of the base-plate;

Fig. 4 is a transverse vertical section through a portion of the pump, being taken 45 upon a plane at right angles to the plane upon which the section of Fig. 1 is taken; and

Fig. 5 is a view illustrating a modified form of construction, a portion of the pump-head sleeves and a portion of the horizontal 50 shaft of the machine being broken away.

Referring to Figs. 1 to 4, in which corresponding parts are indicated by the same reference characters,—

55 10 indicates a base having mounted upon

one end an engine 11 of any suitable type and having mounted upon its opposite end a pump head 12 in centered vertical alignment over the well-tube 13 which is connected to and depends from the discharge 60 head 14 which is supported by a flange 15 resting upon the base 10. A pump shaft 16, supported as hereinafter described, extends down through the discharge head 14, a stuffing-box 17 of any suitable type being secured about the shaft 16 at the upper end of the discharge head 14. The stuffing-box 17 has secured to its lower end the upper end of a shaft protecting casing 18 which serves to protect the shaft 16 and its bearings from the water forced upward through the pump casing 13 and out through the discharge pipe 19. Inasmuch as the pumping mechanism operated by the shaft 16 is to be of any suitable type, it is believed to be 75 unnecessary to illustrate it herein.

The shaft 16 is rovolubly and adjustably supported upon the pump head 12 by means of an anti-friction bearing 20 supported by a housing 21 mounted upon the upper end 80 of the pump head 12, the said bearing 20 being interposed between the housing 21 and a cap 22 which is feathered upon the shaft and is held in adjusted vertical position thereon by means of a screw-threaded nut 23. 85 A pin 24 is employed for holding the nut 23 against rotation as may be desired. The housing 21 provides a chamber 25 about the bearing 20 closed at its upper end by a cap-plate 26. A pipe 27 leads downward from 90 any suitable supply of oil or other appropriate lubricant to the interior of the chamber 25 for lubricating both the anti-friction bearing 20 and another bearing 28 mounted in said housing. The bearing 28 is further 95 lubricated by a supply of oil fed thereto through a pipe 29 communicating through a duct 30 with the interior of said bearing. The shaft 16 is held against upward movement by means of an anti-friction bearing 100 31 interposed between the bottom of the housing 21 and a bevel gear 32 feathered upon the shaft, the gear 32 being adjustable longitudinally of the shaft by means of a nut 33 having screw-threaded engagement 105 with a two-part split collar 34—35, the parts of which are mounted in a groove 36 as is best shown in Fig. 2. An additional bearing 36^a is provided for the shaft 16 below the gear 32, a stuffing-box 37 of any suit- 110

able type being secured about the shaft 16 below the bearing 36^a.

The pump head 12 comprises two horizontally-extending sleeves 38—39 spaced 5 apart from each other, the inner sleeve 39 being provided with two bearings 40—41 for a horizontally-extending shaft 42, each of the bearings 40—41 being provided with an oil duct 43 leading to the shaft 42. A bevel 10 gear 44 is mounted upon the tapered inner end of the shaft 42, being held in position relative to said shaft by means of a key 45 and a nut 46, the gear 44 being adapted to mesh with the gear 32. An anti-friction 15 bearing 47 is interposed between the gear 44 and the bearing 41, serving to take up the end thrust of the shaft 42 toward the left in Fig. 1.

The shaft 42 is connected by means of a 20 suitable flexible coupling 48 with a sleeve 49 which loosely surrounds a short section of shaft 50 which is fixedly connected with the shaft 51 of the engine 11. The sleeve 49 is connected with the shafts 50 and 51 25 through the medium of a friction clutch of any suitable type. In the construction shown the friction clutch comprises a drum 52, a friction band 53 adapted to be tightened about said drum upon a suitable swing- 30 ing movement of an arm 54, and a grooved sleeve 55 by a movement of which toward the left in Fig. 1 the arm 54 is given a swinging movement for tightening the band upon the drum.

35 As is shown by an inspection of Figs. 1 and 4, the pump head 12 is divided by a wall 56 into two chambers 57 and 58, the chamber 57 being in communication with the chamber formed by the sleeves 38 and 39, 40 the outer ends of which are suitably joined together by a vertically-extending wall. The chamber 58 is closed at one side by a cap 59 which has mounted in it a pipe 60 through which the chamber 58 is adapted 45 to be kept full of oil or other suitable lubricant from any suitable source, serving thus to keep the bearings 31, 36^a and 47 and the intermeshing gears 32 and 44 properly lubricated. The chamber 57 is connected by 50 means of a pipe 61 with the water discharge head 14 by means of which a supply of cold water is fed to said chamber about the bearings 40 and 41 and about the chamber 58 in which the gears 32 and 44 are mounted. A 55 pipe 62 at one side of the pump connects the chamber 57 with a chamber 63 formed in the lower end of the housing 21 about the chamber 25 in which the bearing 20 is located. The cold water from the chamber 57 is 60 adapted to rise through said pipe 62 and to escape therefrom through a pipe 64. By this means the working parts of the pump head are all kept properly lubricated and cooled for efficient operation.

65 In Fig. 5 which shows a modified form of

construction, the shaft 42^a is connected to a shaft 65 by means of a flexible coupling 66 of any suitable type. The shaft 65 is supported by suitable bearings 67—68 carried by standards 69—70, respectively, mounted 70 upon the base 10^a, being provided with a heavy fly-wheel 71 fixedly mounted thereon. The shaft 65 is connected by means of a flexible coupling 72 with a sleeve 49^a which in turn is connected by any suitable friction 75 clutch mechanism with any suitable source of power. As shown, the clutch mechanism just referred to comprises a clutch sleeve 55^a and ordinary friction clutch members 71—72, and the source of power referred to 80 is, as shown, an engine, a portion of which is indicated by 73. It is to be understood, of course, that any other suitable clutch mechanism than that just referred to may be employed in lieu of the one shown. As all of 85 the remaining parts of the mechanism are the same as in Fig. 1, the same reference numerals are applied to such parts. By the use of the construction shown in Fig. 5 I am enabled to use a single cylinder internal 90 combustion engine without undue danger of stripping the teeth from the gears.

By the use of a friction clutch for coupling the engine to the pump shaft, I am enabled to apply the power gradually from the 95 engine to the shaft so as to bring the pump gradually up to its full speed driving, being able thus to drive the pump with less power than would be required if it were necessary to start the pump into operation before the 100 engine had assumed its full speed operation.

What I claim as my invention and desire to secure by Letters Patent, is—

1. The combination of a rigid supporting means, a deep well rotary pump head removably mounted thereon, a vertical shaft extending downward from said pump head, an engine having a horizontally-extending drive shaft mounted on said supporting means adjacent to said pump head, and connections between said two shafts, comprising a pair of intermeshing bevel gears non-rotatably mounted upon said shafts respectively, and a flexible coupling operatively connected between said drive shaft and said bevel gears, said vertical shaft being adjustable independently of the adjustment of said bevel gears.

2. The combination of a rigid supporting means, a deep well rotary pump head removably mounted thereon, a vertical shaft extending downward from said pump head, an engine having a horizontally-extending drive shaft mounted on said supporting means adjacent to said pump head, and connections between said two shafts, comprising a pair of intermeshing bevel gears non-rotatably mounted upon said shafts respectively and a friction clutch operatively connected between said bevel gears and said 130

drive shaft, said vertical shaft being adjustable independently of the adjustment of said bevel gears.

3. The combination of a rigid supporting means, a deep well rotary pump head removably mounted thereon, a vertical shaft extending downward from said pump head, an engine having a horizontally-extending drive shaft mounted on said supporting means adjacent to said pump head, and connections between said two shafts, comprising a friction clutch and a flexible coupling operatively connected in series with said drive shaft, and a pair of intermeshing bevel gears operatively connected between said flexible coupling and said vertical shaft, said vertical shaft being adjustable independently of the adjustment of said bevel gears.

20 4. The combination of a vertical rotary pump shaft, a horizontally-extending rotary shaft, intermeshing bevel gears operatively connecting said two shafts, means for adjusting said vertical shaft independently of the adjustment of said bevel gears, a third shaft, a flexible coupling connecting said third shaft with said second-named shaft, an engine, and a friction clutch for connecting said third shaft with said engine.

25 5. The combination of a vertical rotary pump shaft, a horizontally-extending rotary shaft, intermeshing bevel gears operatively connecting said two shafts, means for adjusting said vertical shaft independently of the adjustment of said bevel gears, an engine, a drum adapted to be rotated by said engine, a sleeve revolvably mounted upon the axis of rotation of said drum, a friction 30 clutch member carried by said sleeve and adapted to have frictional engagement with said drum, and a flexible coupling connecting said sleeve with said second-named shaft.

45 6. The combination of a vertical rotary pump shaft, a gear mounted on said shaft, means for adjusting said vertical shaft independently of the adjustment of said gear, an engine, and flexible driving connections 50 between said engine and said gear, comprising a shock absorber means adapted to take up the sudden stresses of the engine and prevent their reaching said gear.

55 7. The combination of a vertical rotary pump shaft, a gear mounted on said shaft, means for adjusting said vertical shaft independently of the adjustment of said gear, an engine, and flexible driving connections 60 between said engine and said gear, comprising a heavy balance wheel adapted to take up the sudden stresses of the engine and prevent their reaching said gear.

8. The combination of a vertical rotary pump shaft, a horizontal rotary shaft adjacent thereto, intermeshing gears connect-

ing said two shafts, means for adjusting said vertical shaft independently of the adjustment of said gears, an engine, and driving connections between said engine and said horizontal rotary shaft, comprising a 70 flexible coupling and a heavy balance wheel adapted together to take up the sudden stresses of the engine and prevent their reaching said gears.

9. The combination of a vertical rotary 75 pump shaft, a horizontal shaft adjacent thereto, intermeshing gears connecting said two shafts, means for adjusting said vertical shaft independently of the adjustment of said gears, an engine, and driving connections between said engine and said horizontal shaft, comprising a flexible coupling and a heavy balance wheel adapted together to relieve the sudden stresses of the engine and prevent their reaching said 80 gears, and a friction clutch by which the power from the engine may be applied gradually to said vertical pump shaft.

10. The combination of a vertical rotary pump shaft, a horizontally-disposed flexible 90 coupling, intermeshing bevel gears between said flexible coupling and said vertical pump shaft, means for adjusting said vertical shaft independently of the adjustment of said bevel gears, an engine, and a friction 95 clutch interposed between said engine and said flexible coupling.

11. The combination of a vertical rotary pump shaft, a horizontally-disposed flexible 100 coupling, intermeshing bevel gears between said flexible coupling and said vertical pump shaft, means for adjusting said vertical shaft independently of the adjustment of said bevel gears, an engine, a second horizontally-disposed flexible coupling 105 operatively connected with said engine, a shaft interposed between said flexible couplings, and a heavy balance wheel fixed on said second-named shaft.

12. The combination of a vertical rotary 110 pump shaft, a horizontally-disposed flexible coupling, intermeshing bevel gears between said flexible coupling and said vertical pump shaft, means for adjusting said vertical shaft independently of the adjustment 115 of said bevel gears, an engine, a second horizontally-disposed flexible coupling, connections between said last-named flexible coupling and said engine comprising a friction clutch, a shaft interposed between said 120 flexible couplings, and a heavy balance wheel fixed on said last-named shaft.

13. A driving means for a deep well rotary pump comprising in combination a horizontal shaft, a vertical adjustable shaft, 125 a pair of intermeshing beveled gears mounted on said two shafts, respectively, whereby said vertical shaft is driven from said horizontal shaft, the gear on the vertical shaft being held up and adjusted to the changed 130

position of the shaft by a screw-threaded collar or sleeve on said vertical shaft.

14. A driving means for a deep well rotary pump comprising in combination a horizontal shaft, a vertical adjustable shaft, a pair of intermeshing bevel gears mounted on said two shafts, respectively, whereby said vertical shaft is driven from said horizontal shaft, said vertical shaft having an external screw-threaded removable collar and an internally screw-threaded sleeve which coacts with said external screw-threaded collar for supporting and adjusting the gear on said vertical shaft, said bevel gears being provided with anti-friction thrust bearings and a cooling means for absorbing the heat generated.

15. A driving means for a deep well rotary pump comprising in combination a horizontal shaft, a vertical adjustable shaft, a pair of intermeshing bevel gears mounted on said two shafts, respectively, whereby said vertical shaft is driven from said horizontal shaft, and means for adjusting said vertical shaft vertically independent of the adjustment of said bevel gears.

16. A driving means for a deep well rotary pump comprising in combination a horizontal shaft, a vertical adjustable shaft, a pair of intermeshing bevel gears mounted on said two shafts, respectively, whereby said vertical shaft is driven from said horizontal shaft, thrust means mounted around the vertical shaft, and means for relieving said thrust means from the thrust of said bevel gears.

17. A driving means for a deep well rotary pump, comprising in combination a horizontal shaft, a vertical adjustable shaft, a pair of intermeshing bevel gears mounted on said two shafts, respectively, whereby said vertical shaft is driven from said horizontal shaft, means for adjusting said vertical shaft vertically independently of the position of said bevel gears, a thrust bearing for said vertical shaft and means for relieving said thrust bearing from the thrust of said bevel gears.

18. In a deep well rotary pump, the combination of a vertical pump shaft, a horizontal drive shaft, a pair of intermeshing bevel gears non-rotatably but adjustably mounted on said shafts respectively, said vertical shaft having a screw-threaded upper end portion, a nut on such end portion by the turning of which the vertical shaft may be adjusted independently of the adjustment of the gear thereon, a thrust bearing for taking the thrust of said vertical shaft, and means for relieving such bearing of the thrust of said bevel gears.

19. The combination of a pump head, a pump shaft extending downward from said pump head, a horizontally-extending shaft journaled in said pump head adjacent to said

first-named shaft, intermeshing bevel gears operatively connecting said two shafts, said downwardly extending shaft being adjustable independently of the adjustment of said bevel gears, and means for feeding a supply of water to said pump head about said second-named shaft for cooling it.

20. The combination of a pump head, comprising a hollow casing, a bearing sleeve extending through said casing, a horizontally-extending shaft journaled in said sleeve, a pump shaft extending downward from said pump head, intermeshing bevel gears operatively connecting said two shafts, said downwardly extending shaft being adjustable independently of the adjustment of said bevel gears, and means for feeding a supply of water to said casing about said bearing sleeve for cooling said shaft.

21. The combination of a pump head, comprising two chambers one of which extends substantially about the other, a pump shaft extending downward through the inner chamber, a second shaft extending horizontally into said inner chamber, intermeshing bevel gears in said chamber operatively connecting said two shafts, said downwardly extending shaft being adjustable independently of the adjustment of said bevel gears, and means for feeding a supply of water to the outer chamber for cooling said shafts and gears.

22. The combination of a pump head, comprising two chambers one of which extends substantially about the other, a pump shaft extending downward through the inner chamber, a second shaft extending horizontally into said inner chamber, intermeshing bevel gears in said inner chamber operatively connecting said two shafts, said downwardly extending shaft being adjustable independently of the adjustment of said bevel gears, and means for feeding a supply of oil to said inner chamber about said shafts and said gears.

23. The combination of a pump head, comprising two chambers one of which extends substantially about the other, a pump shaft extending downward through the inner chamber, a second shaft extending horizontally into said inner chamber, intermeshing bevel gears in said inner chamber operatively connecting said two shafts, said downwardly extending shaft being adjustable independently of the adjustment of said bevel gears, means for feeding a supply of oil to said inner chamber about said shafts and said gears, and means for feeding a supply of water to the outer chamber for cooling said shafts and said gears.

24. The combination of a pump head, comprising two chambers one of which extends substantially about the other, a pump shaft extending downward through the inner chamber, a second shaft extending hori-

zontally into said inner chamber, intermeshing bevel gears in said inner chamber operatively connecting said two shafts, said downwardly extending shaft being adjustable independently of the adjustment of said bevel gears, anti-friction thrust bearings for said gears within said inner chamber, and means for feeding a supply of oil to said inner chamber about said bearings and said gears.

25. The combination of a pump head, comprising a hollow casing, a pump shaft extending downward through said casing, a bearing member removably mounted in the bottom wall of said casing about said shaft, packing carried by said bearing member about said shaft, gear means located in said casing for driving said shaft, said downwardly extending shaft being adjustable independently of the adjustment of said gear means, and means for feeding a supply of oil to said casing above said bearing and said packing.

26. The combination of a pump head, a pump shaft extending downward from said pump head, adjustable supporting means carried by said pump head for supporting said shaft therefrom, and a gear feathered upon said shaft, anti-friction bearing means fixedly mounted above said gear adapted to receive the upward thrust of said gear, said gear being adjustable along said shaft independently of said shaft adjustment.

27. The combination of a pump head, a pump shaft extending downward from said pump head, adjustable supporting means carried by said pump head for supporting said shaft therefrom, a gear feathered upon said shaft, anti-friction bearing means fixedly mounted above said gear adapted to receive the upward thrust of said gear, a split collar in a groove in said shaft below said gear, and a nut adjustably mounted by means of screw-threads upon said split collar whereby said gear may be independently adjusted on said shaft.

28. The combination of a pump head, a shaft extending downward from said pump head, a bevel gear mounted on said shaft,

a second shaft revolvably mounted in said pump head and extending toward said first-named shaft and having its inner end tapered, and a second bevel gear secured on the tapered end of said second shaft and meshing with said first-named bevel gear for driving said first-named shaft, said downwardly extending shaft being adjustable independently of the adjustment of said bevel gears.

29. The combination of a pump head, a shaft extending downward from said pump head, a bevel gear mounted on said shaft, a second shaft revolvably mounted in said pump head and extending toward said first-named shaft and having its inner end tapered, and a second bevel gear secured on the tapered end of said second shaft and meshing with said first-named bevel gear for driving said first-named shaft, said first-named gear being adjustable longitudinally of said first-named shaft for securing proper coöperation between said two gears independently of the adjustment of said downwardly extending shaft.

30. A driving means for a deep well rotary pump, comprising in combination a horizontal shaft, a vertical adjustable shaft, a pair of intermeshing bevel gears mounted on said two shafts, respectively, whereby said vertical shaft is driven from said horizontal shaft, means for adjusting said vertical shaft vertically, and independently adjustable means mounted on the vertical shaft below a bearing forming a part of the frame support for receiving the upward thrust of said vertical shaft.

31. A driving means for a deep well rotary pump, comprising in combination a horizontal shaft, a vertical adjustable shaft, a pair of intermeshing bevel gears mounted on said two shafts, respectively, whereby said vertical shaft is driven from said horizontal shaft, said vertical shaft having a screw-threaded collar that co-acts with the bevel gear through which said vertical shaft passes, and a thrust bearing to prevent any upward movement of said vertical shaft.

LARS W. BODINSON.
